UNITED STATES PATENT OFFICE.

HENRY PRICE BALL, OF BROOKLYN, ASSIGNOR TO THE EDISON GENERAL ELECTRIC COMPANY, OF NEW YORK, N. Y.

SAFETY-PLUG.

SPECIFICATION forming part of Letters Patent No. 460,548, dated October 6, 1891.

Application filed December 1, 1890. Serial No. 373,172. (No model.)

To all whom it may concern:

Be it known that I, HENRY PRICE BALL, a citizen of the United States, residing at Brooklyn, in the county of Kings and State of New York, have invented a certain new and useful Improvement in Safety-Plugs, of which the following is a specification.

The invention relates to devices commonly known as "safety-catches" or "safety-plugs"— that is, to devices placed in electrical circuits— which devices are adapted to conduct a normal current used in the system to which they are applied, but which when an abnormal current passes through the line and through said catches burn or melt, and thus open the circuit, stopping the flow of current, and preventing damage to translating devices in the circuits.

The present invention consists in an improved holder for the cut-outs of the character described, and in the several combinations hereinafter described and claimed.

In the accompanying drawings, illustrating the invention, Figure 1 is a plan view of the holder and cut-out. Fig. 2 is a side view thereof, and Fig. 3 is a section on line $x-x$ of Fig. 1.

It is very desirable that the fusible portion of the cut-out should be open to inspection, and at the same time it should be protected from mechanical injury, but should not be so tightly inclosed as to confine the gases which may be formed suddenly when the fuse burns. All these ends are attained in a very simple and efficient manner in the device to be described. A holder for the safety-catch illustrated is shown of proper shape to fit the well-known Edison socket; but it is evident that it might equally well be adapted to fit other sockets. The body of the holder I prefer to make of glass or hard rubber cast or molded into the desired shape, although other materials may be employed. The body of the holder is in the form of a cup having an inner ledge 1 and a rim 2. The rim has at suitable points projections extending inward, as shown at 3, which may be formed integral

with the rim or may be made separately and secured thereto. At one or more points notches are cut in the underside of the rim, as clearly shown at 4. These notches are preferably directly under the projections 3. 5 and 6 are the metal terminals of the fuse adapted to co-operate with corresponding terminals in a socket in which the plug is placed. To the former terminal is soldered or otherwise secured a copper or other strip 7, to which is soldered the fusible conductor 8. Evidently the latter conductor might be connected directly to terminal 5. The opposite end of the conductor 8 is connected to terminal 6 to complete the circuit when the plug is placed in its socket. Above the fusible conductor is placed a cover or diaphragm 9, which I prefer to have of flexible and transparent material, such as mica, in order that it may be bent to pass under the lugs or projections 3, and thus be held securely in place, and so that the fusible conductor may be seen without removing the cover.

When the diaphragm rests on the ledge, as shown, the cup in which the fusible conductor is held is tightly closed, so that dust, moisture, &c., will be excluded; but should said conductor burn and volumes of gas be generated, the pressure of the gas will raise the movable cover, (the thickness of the cover being less than the distance between the ledge and the under side of the lugs 3,) allowing gas to escape through the openings 4 above described. The melted metal of the conductor would, however, be held in the cup, and all danger of fire or accidents to persons handling the holder is avoided.

The diaphragm can readily be sprung out and a new fusible conductor put in place, and the diaphragm returned to position.

Having thus described the invention, what I claim is—

1. A holder for fusible conductors, consisting of a cup-shaped body supporting said conductors, a rim having lugs and notches below the lugs, and a cover supported below the lugs and normally closing the body, but

movable to allow the escape of gas, substantially as described.

2. A holder for fusible conductors, consisting of a cup-shaped body, a cover for the cup, 5 means for holding the cover on the cup, a rim on the cup around the cover, said rim being notched, whereby when the cover is raised slightly a passage will be open between the

cup and the external air, substantially as de-
scribed.

This specification signed and witnessed this
22d day of November, 1890.

HENRY PRICE BALL.
